HAND PUNCH

Arthur E. Heise, Woodbridge, Conn., assignor to
The Wm. Schollhorn Company, New Haven,
Conn., a corporation of Connecticut

Application April 11, 1932, Serial No. 604,641

10 Claims. (Cl. 164—120)

This invention relates to hand punches, such, for example, as those used for cancelling tickets. Such punches are arranged to cut out apertures of various shapes in thin sheets of paper or card-board. Thus, they may be arranged to punch round holes, or holes in the shape of clubs, diamonds, hearts, spades, numerals, and various other configurations.

The invention relates more particularly to hand punches of extremely low cost and selling price—punches which retail, for example, for from ten to fifty cents each.

The principal object of the present invention is to provide improvements in the construction of such punches which render them more convenient and satisfactory to use without appreciably increasing the cost of manufacture. Among the specific objects of the invention are the following:

To provide in a hand punch of low cost, mechanism for protecting the punch and die against injury from attempts by the user to squeeze the punch too tightly or to punch therewith thicker material than that for which the punch is intended; to provide a hand punch of low cost having a stripper device which will not mark the work and which is effective in operation; to provide in a hand punch of low cost a retainer for the punched-out material which will not permit this material to escape.

The various features of the invention are illustrated in the accompanying drawing and set forth in the following description. The embodiments of the invention herein shown and described are, however, to be considered as merely illustrative of the principles of the invention, and changes may be made in the construction of the punch and still make use of the invention, the scope of which is indicated in the claims appended hereto.

In the accompanying drawing Fig. 1 is a side elevation of one form of my improved hand punch;

Fig. 2 is a vertical longitudinal section, drawn to an enlarged scale, taken through the jaws and pivot of the punch shown in Fig. 1, the jaws being in open position;

Fig. 3 is a view similar to Fig. 2 except that the punch is shown in closed position;

Fig. 4 is a plan view of the parts shown in Figs. 2 and 3;

Fig. 5 is a transverse vertical section taken on line 5—5 of Fig. 3;

Fig. 6 is a side elevation drawn to a slightly smaller scale than Fig. 1 of a modification of the invention this form of punch being of somewhat

more rugged construction and intended for heavier duty than the punch shown in Fig. 1;

Fig. 7 is a central longitudinal section taken through the jaws of the punch of Fig. 6, and with the addition of a device for retaining the "confetti" or punched-out material.

Referring now to the accompanying drawing, and first to Figs. 1 to 5, inclusive, there is here shown a punch having cross levers 1 and 2 pivoted at 3 by means of a rivet. The cross levers extend to the right to form handles 4 and 5 and to the left to form jaws 6 and 7. These parts are punched out of sheet metal of suitably heavy gauge and then formed by stamping in a press to produce the rounded outer handle surfaces shown in Fig. 1 which are hollow on the inside, and also to produce jaw frames which are reinforced by flanges.

Thus, the upper or punch jaw 6 consists of a flat web or face 8 along each side of which are flanges 9 and 10. Similarly jaw 7 consists of a web or face 11 having side flanges 12 and 13. The flanges 9 and 10 and the flanges 12 and 13 form between them channels each of which is preferably closed at its outer end by a continuance of the respective flanges. This gives the nose of the punch a neat appearance, and the curved outer end portion of the lower or die jaw serves as a guide to facilitate the entrance of the material to be punched.

The two cross levers 1 and 2 are mortised together at the hinge or pivot 3 as may be seen more particularly in Fig. 4, the side plates of cross lever 2 passing between the side plates of cross lever 1. A helical spring 14 surrounds the pivot pin 3, one end thereof projecting into engagement with the inner surface of the hollow handle 5 and the other end similarly extending into engagement with the inner surface of the hollow handle 4. The extension of the spring within handle 4 is preferably formed into a loop 15 located adjacent the outer end of the handle, by which the punch may be suspended on a finger of the hand when not in use. It will be understood that spring 14 biases apart the jaws of the punch.

The jaw frames 6 and 7 are identical in construction except for the fact that the face 8 of jaw 6 has a punch 16 mounted thereon, and the face 11 of jaw 7 is provided with a die 17. Punch 16 is reduced in diameter at its upper end and inserted in a suitable aperture in face 8 and held therein by peening over the reduced portion to form a head 18.

Die 17 is formed by upsetting the outer portion

- of jaw face 11 so as to displace the outer surface of the die slightly from the surface of the jaw face, and then forming an opening in this upset portion corresponding in configuration to the 5 punch 16. In the examples shown in the drawings the punch and die are round, but it will be understood that they may be made of any suitable shape, some of which were mentioned at the beginning of this specification.
- 10 By making the jaws 6 and 7 identical in formation the blanks for the cross levers 1 and 2 are identical in their original configuration, and hence are punched out by the same punch and die. Also, the same forming punch and die are 15 used to provide the curved formation of both handles 4 and 5 and the channeled or flanged construction of both jaws 6 and 7. Hence, up to this point in the manufacture of the punch, the two cross levers 1 and 2 are identical. Subsequently to this the side plates of cross lever 1 are expanded, as shown in Fig. 4, by means of a stamping operation so as to permit the mortising of lever 2 within lever 1. After this the punch 16 and the die 17 are placed on the respective jaws of the levers 1 and 2.

It is important in a hand punch of this sort to provide a stop for limiting both the closing and the opening movement of the punch jaws. If such a stop is not provided the too tight 30 squeezing of the handles will force the inner surface of the punch 16 against the wall of the die, causing undue wear upon both of these parts and also tending to loosen the punch from its seat. It will be understood that undue wear may 35 take place in this way since in a punch which is built to sell in the price class of the present punch both the punch and die are made of mild steel and neither are hardened otherwise than by the hardening effect produced by the cold 40 working of the metal.

Moreover, in order to prevent a prohibitive increase in the cost of manufacture of the punch, this stop must be of extremely simple construction and easily applied to the punch during manufacture. In accordance with the present invention, in order to provide this stop, the web or face 8 of the punch jaw 6 is provided with an aperture 19 which preferably is open at one 45 end where it intersects the inner end of web 8 as may be seen in Figs. 2 and 4. A stop pin 50 20 is fixed to the web or face 11 of jaw 7 near its inner end. This stop pin is provided with an enlargement 21, which abuts against the upper surface of face 11, and also with a head 22. Stop pin 20 is conveniently in the form of a screw having its lower end tapped into face 11, and while enlargement 21 may be made integral with pin 20 it preferably consists of a collar through which the pin 20 passes. By having 55 the aperture 19 open at one end, pin 20 can be placed in position even though enlargement 21 is integral with the pin.

The punch is also provided with a stripper 23, which in the form of punch shown in Figs. 1 60 to 5, inclusive, comprises one leg of a substantially U-shaped strip of resilient metal such as spring steel, the other leg of which constitutes a cover 24 for the channel formed between flanges 12 and 13 of the die jaw 7 so as to retain therein 65 the "confetti" or punched-out material. The substantially U-shaped strip of metal just referred to is preferably fixed in position by the stop pin 20 which has a shoulder 25 which clamps the rear portion of the stripper 23 against the 70 top of enlargement or collar 21.

Hence, when the jaws of the punch are closed as shown in Fig. 3, the movement of the jaws is limited by the engagement of the upper surface of stripper 23 opposite enlargement 21 with the lower surface of web or face 8 of jaw 6 adjacent the aperture 19. This limits the extent to which punch 16 may enter the die 17. When the handle of the punch is again released and the jaws opened, the extent of this movement is limited by the engagement of the head 22 of the pin 20 with the upper surface of web 8 as shown in Fig. 2.

During this opening movement, the stripper 23 is engaged by the paper or other material which has been punched so as to cause the punch 16 to be withdrawn from the aperture made in the paper, or, in other words, the punched material is stripped from the punch 16. It will be understood that stripper 23 is provided with an aperture 26 somewhat larger than the punch 16 so that the punch will be freely movable therethrough. Also the outer end of the stripper 23 is bent upwardly so as to serve as a guide to direct the paper between the jaws of the punch. As previously mentioned, the curved outer nose of the jaw 7 serves as a coacting guide.

Although stripper 23 is secured to the jaw 7 at only one point, the portion of the stripper beyond pin 20, that is, the bottom of the U-shaped piece fits snugly between the flanges 12 and 13 just beyond the end of web 11, and thereby the U-shaped strip is held against lateral motion.

The cover portion 24 of the U-shaped strip is preferably provided with shallow internal flanges 27 which may be seen in Figs. 2, 3 and 5 and which 110 form convenient means for producing a tight fit between the cover 24 and the upper edges of the flanges. In order to remove the punched-out material from the retaining space between flanges 12 and 13 the cover 24 is moved outwardly to the 115 dotted position shown in Fig. 3, and in order to provide a convenient means for grasping this cover with the fingers the outer end of the cover preferably projects slightly beyond the nose of the punch.

In Fig. 3 a sheet 28 has been inserted in the punch and a hole punched therein. It will be observed that the pressure of punch 16 during the punching operation, together with the friction of the walls of the punched hole with the outer surface of the punch maintains the sheet against the surface of die 17, the stripper 23 not having made contact with the sheet except insofar as it served as a guide for the insertion of the sheet. During the opening of the punch jaws stripper 23 will 120 move into contact with the sheet 28 and strip the sheet from contact with the punch 16. The pressure exerted by the stripper, however, will be only that necessary to overcome the friction of the walls of the punched holes with the surface 125 of the punch, and this is insufficient to produce a mark upon the surface of the sheet 28.

In prior punches of this type it has been customary to mount a relatively stiff spring stripping piece upon the punch jaw, this spring extending 130 downwardly slightly below the end of the punch. This type of stripper made contact with the sheet being punched ahead of the end of the punch, and during the punching operation the stripper had to be flexed. Accordingly, considerable pressure was exerted by the stripper which caused an undesirable marking of the sheet. Moreover, as the stripper was necessarily 135 comparatively stiff, it increased the amount of pressure required to operate the punch. With the 140 145 150

stripper of the present invention, however, there is no marking of the work and the punch is easier to operate.

In the modified form of punch shown in Figs. 5, 6 and 7, the cross levers 29 and 30 together with the punch jaws and handles are stamped from sheet material after the manner of the punch previously described. The handles, however, are subjected to a further stamping operation which 10 turns the inner margins 31 of the flanges inwardly into abutting relation so that although the handles are hollow they have continuous surfaces on the inside as well as the outside, thereby presenting the appearance of a cast instead of a stamped product.

To carry out this same effect, the flanges 32 of the punch jaws are made straight instead of curved. Also, the biasing spring instead of being carried upon the hinge is made in the form of a straight helical spring 34 which extends between the handles. In order to maintain spring 34 straight a rigid core 35 is loosely carried within the interior of the spring. The stop pin or screw 20a is similar in construction to that previously described and operates in the same manner.

The punch of Figs. 6 and 7 is of heavier construction and adapted to punch larger holes than that shown in the previous figures of the drawings. It is necessary to provide a sturdier stripper. This stripper 36 is made in the form of a substantially rigid bar, which is secured to the die jaw by means of the stop pin 20a as before. The tail portion 37 which extends between the flanges 33 of the die jaw and fits snugly therebetween also as before prevents sidewise movement of the stripper.

If it is desired to provide this form of punch with a retaining chamber for clipping, the tail portion 37 of the stripper is extended to the surface of flanges 33 passing in close proximity to the end 38 of the web or face of the die jaw. Then a strip 39 of resilient material, such, for example, as spring steel is bent to substantially the shape indicated in Fig. 7, having a reentrant portion 40 which fits loosely over the hinge pin. The upper leg of this strip 39 overlies the channel between flanges 32 and forms a finish for the punch jaw which conceals the channel construction as well as the head of the punch 16a and head of the stop pin 20a. The lower leg of strip 39 similarly engages the flanges 33 and forms a cover for the space between these flanges so as to hold the clippings therein.

In order to discharge the clippings the end of this lower leg extends beyond the end of the lower jaw so that it may be engaged by the finger. Strip 39 is substantially flat in cross section and fits loosely between the side plates of the cross levers so that its resilient legs are free to contact with the two punch jaws. It is prevented from longitudinal movement by the engagement of the reentrant section 40 with the hinge pin. Since the two legs of strip 39 are of similar shape and appearance, they impart a similarity of appearance to the two jaws of the punch. If desired, however, the lower leg portion of strip 39 may be provided with reentrant flanges similar to the flanges 27 of Fig. 5.

I claim:

70 1. In a hand punch, the combination with pivoted cross levers, of jaws carried thereby one of which has outwardly extending flanges along the sides of its face said face having an aperture therein, a spring for urging the jaws apart, a post on said other jaw and extending through

said aperture, said post having an enlargement at its base for coacting with the inner surface of said flanged jaw to form a stop limiting the extent to which the jaws can be closed, and said post having a head coacting with the outer surface of said flanged jaw to limit the opening of the jaws.

2. In a hand punch the combination with pivoted cross levers, of a pair of coacting jaws carried thereby, a punch mounted upon one of said jaws, a die carried by the other of said jaws, a stripper member comprising a bar mounted in parallel relation to said die jaw, a pin for securing said bar to the face of the die jaw, said bar having a tail portion on the pivot side of said pin, and surfaces at least a part of which is on said die jaw cross lever engaging said tail portion on the pivot side of said pin so as to hold the stripper bar against lateral movement.

3. In a hand punch the combination with pivoted cross levers, of a pair of coacting jaws carried thereby having outwardly extending flanges at the sides of the jaw faces, a die on the inner face of one of said jaws and a coacting punch on the inner face of said other jaw, a stripper comprising a bar arranged in parallel relation to the inner face of said die jaw, and a pin for securing said bar to the face of said jaw, said bar having a tail portion at least a part of which is on the pivot side of said pin and fits between the flanges of the die jaw on the pivot side of said pin, thereby holding said bar against sidewise movement.

4. In a hand punch, the combination with cross levers, of jaws carried thereby, one of which has a channel on its outer face and a die on its inner face, a strip of resilient metal overlying said channel and secured to said jaw thereby closing the space within said channel to form a retaining chamber for punched-out material, said chamber being opened for the discharge of material therefrom by the flexing of said resilient strip.

5. In a hand punch, the combination with cross levers, of jaws carried thereby, one of which has a channel on its outer face and a die on its inner face, a strip of resilient metal overlying said channel and secured to said jaw thereby closing the space within said channel to form a retaining chamber for punched-out material, said strip having inwardly directed shallow flanges fitting between the side walls of the channel so as to form a tight joint therewith, said chamber being opened for the discharge of material therefrom by the flexing of said resilient strip.

6. In a hand punch, the combination with cross levers of jaws carried thereby, one of which has a channel at its outer face and a die on its inner face, a punch on the other jaw, a substantially U-shaped strip of resilient metal fixed to the jaw which carries the die, one leg of said strip serving as a stripper for said punch, and the other leg thereof serving as a cover for said channel so as to retain therein the punched-out material.

7. In a hand punch, the combination with pivoted cross levers, of jaws carried thereby having outwardly extending flanges at the sides of the jaw faces, a die on the inner face of one of said jaws and a coacting punch on the inner face of said other jaw, a spring for urging the jaws apart, the face of the punch jaw having an aperture therein between the punch and said pivot, a post fixed to the die jaw and extending through

- said aperture said post having an enlargement at its base for coacting with the inner face of the punch jaw to form a stop limiting the closing movement of the jaws, said post also having a head coacting with the outer face of the punch jaw limiting the opening movement of said jaws, and a U-shaped strip of resilient material fixed to said post, one leg of said strip extending outward and serving as a stripper for the punch, and the remaining portion of said strip serving as a closure for the space between the flanges of the die jaw and providing a retainer for punched out material.
8. In a hand punch, the combination with cross levers, of jaws carried thereby, one of which has a channel on its outer face and a die on its inner face, a stripper of resilient metal secured to said jaw and extending laterally from the rear end of said jaw between the faces of said channel to form with said channel the rear end of a retaining chamber for punched-out material, said strip also extending longitudinally of the punch and coacting with the outer edges of said chamber to form the outer wall of said chamber, said chamber being opened for the discharge of material therefrom by the flexing of said resilient strip.
9. In a hand punch, the combination with pivoted cross levers, of a pair of coacting jaws carried thereby, one of which has outwardly extending flanges on the sides of its face, a die carried by said jaw and a punch mounted upon the other of said jaws, a stripper member comprising a bar mounted in parallel relation to the face of said die jaw, means for attaching said bar to said jaw, said bar having a portion extending laterally at the rear end of said face between the said flanges and forming the rear wall of a retaining chamber for punched-out material, and means coacting with said flanges and the laterally extending portion of said bar to form the outer wall of said retaining chamber.
10. In a hand punch, the combination with cross levers, of jaws carried thereby, each of which has a channel on its outer face and a punch member on its inner face, a pin for pivoting said cross levers the one on the other, and a substantially U-shaped strip of resilient metal attached to said pivot pin, one leg of said strip overlying each of said channels.
